UNITED STATES PATENT OFFICE.

ROBERT JAMIESON, OF HOPEDALE, MASSACHUSETTS, ASSIGNOR TO DRAPER CORPORATION, OF HOPEDALE, MASSACHUSETTS, A CORPORATION OF MAINE.

LOOM-SEAT.

1,312,251.

Specification of Letters Patent.

Patented Aug. 5, 1919.

Application filed August 13, 1918. Serial No. 249,642.

To all whom it may concern:

Be it known that I, ROBERT JAMIESON, a citizen of the United States and resident of Hopedale, county of Worcester, State of Massachusetts, have invented an Improvement in Loom-Seats, of which the following description, in connection with the accompanying drawing, is a specification, like characters on the drawing representing like parts.

This invention relates to improvements in loom seats and the object thereof is to provide a seat for the operator of a series of looms or other machinery which will be so constructed and arranged that it will present a firm and durable seat while in operative position, occupying a minimum amount of space and when not in use may be folded closely against the side of the loom or other machine, thereby leaving the passage around the machine free from obstruction.

One of the objects of the present invention is to provide a loom seat which is capable of being folded against the loom frame and retained in such inoperative position and which when brought to horizontal or operative position will be securely locked in that position so that the operator can leave the seat and again resume it without the necessity of looking behind him.

A further feature of the invention consists in providing means for locking the loom seat either in operative horizontal position or in substantially vertical inoperative position which will prevent the seat from assuming and remaining in any intermediate position so that the loom seat when removed from operative position cannot project into the alleyway between the looms.

Another object of the invention is to provide a loom seat of the character described which will be simple in construction and of maximum strength.

Other objects and features of the invention will more fully appear from the following description, the accompanying drawings, and will be pointed out in the annexed claims.

In the drawings:

Figure 1 illustrates a portion of a loom frame with a preferred form of loom seat secured thereto.

Fig. 2 is a view partly in section on lines 2—2 Fig. 1 looking toward the loom frame.

Fig. 3 is a horizontal sectional view on line 3—3 Fig. 2, and,

Fig. 4 is a detail sectional view through the end of the arm of the loom seat showing the locking plunger engaging the locking surface thereof.

Inasmuch as the loom seat attachment forming the subject matter of my invention is applicable to almost any type of loom only a part of the vertical portion of the loom side or frame is illustrated herein with the seat attachment secured thereto.

In the construction illustrated the loom frame is made of channel or angle iron presenting a flange 2 and the bracket which supports the loom seat is so constructed as to be readily secured to this form of frame. The bracket desirably is of somewhat box-like construction and is formed in two parts which enable it to be clamped about the flanged vertical edge of the loom frame. The main part of the bracket is of substantially L-shape, presenting walls 3 and 4 at right angles to each other, the inner edge 5 of the wall 3 being adapted to rest against the flat face of the frame 1. The other portion of the bracket comprises a plate 6 which abuts at one end against the edge 7 of the wall 4 and has an integral offset side 8 extending alongside the flange 2 of the frame and terminating in an extension 9 which lies parallel to the side of the frame.

The plate 6 desirably is provided with lugs 10, 11 adapted to engage respectively the inner face of the wall 4 and the outer face of the flange 2 to position the parts of the bracket properly. The main portion 3 of the bracket and the plate 6 are secured together by a bolt 12 which extends through the same adjacent to the outer edge of the flange 2.

In order to secure the parts of the bracket firmly together and to the loom frame, notwithstanding any inequalities which may exist in the latter adjustable means, such as one or more thrust screws 13 are passed through the extension 9 of the plate 6 and abut against the inner side of the loom frame 1. The wall 3 of the main portion of the bracket is provided with a laterally offset and upwardly extending ear 14 which forms a journal for a pin 15, the opposite end of which is supported in an ear 16 extending upwardly from the wall 4 of said

main portion of the bracket. The main portion of the bracket is also provided with an upwardly extending member 17 which may be arcuate in form and which terminates in 5 a hook-like extension 18 having a flat under face 19 which serves as an abutment to retain the seat in horizontal position as will hereinafter be more fully explained.

The seat 20 may be and is of the usual 10 circular form and is carried at the outer end of an arm 21 which is journaled at its inner end upon the pivotal shaft or pin 15. The inner end of the arm 21 is provided with an integral upward and lateral extension 22 15 which when the seat is in horizontal position engages the flat under face 19 of the hook-like extension 18 of the member 17. By constructing the member 17 in arcuate form space is provided which will permit the 20 extension 22 to swing downwardly when the seat 20 is raised into vertical or inoperative position against or adjacent the loom frame.

The inner end of the arm 21 is also provided 25 with a laterally offset portion 23 which forms an increased bearing area upon the shaft 15 and also provides a means for locking the seat in horizontal or vertical positions. The extension 23 is provided 30 with an under flat face 24 and an end flat face 25 which are alternatively adapted to be engaged by the head 26 of a plunger 27 which is reciprocably mounted in a cylindrical bore 28 in the corner portion of the main 35 member of the bracket. The plunger 27 desirably is provided with a central stem 29 extending centrally down through the bore 28 and slidably mounted in a bearing 30 in the lower end of said bracket, the bore 28 40 extending nearly the full distance through the member and terminating a sufficient distance from the bottom thereof to provide for the bearing 30. The plunger 27 is normally forced upwardly by a helical spring 45 31 which is coiled about the stem 29 of the plunger and rests at its lower end upon the upper face of the bearing 30 and at its upper end engages the base of the plunger 27.

50 The head 26 of the plunger thus being adapted to engage either the surface 24 upon the bottom of the arm 21 which carries the seat 20 or the flat face 25 at the end of said arm is enabled to lock the seat 55 either in the horizontal position illustrated in Fig. 1 or in the vertical position illustrated in dotted lines in said figure.

When the seat is pulled down to horizontal operative position there not only is 60 no tendency of the seat to move to inoperative position but it is locked against such movement whereas when the seat is moved to vertical or inoperative position the engagement of the plunger 26 with the face

25 at the end of the arm 21 effectively prevents the seat from dropping back to horizontal position. 65

It will thus be seen that the seat may be positively locked in either horizontal or substantially vertical position. It will be 70 observed that the construction thus described is of a simple character and is strong and durable.

It will be understood that the particular construction disclosed herein is of an illustrative character and is not restrictive and that various modifications may be made within the spirit and scope of the following 75 claims.

Having thus described my invention what 80 I claim as new and desire to secure by Letters Patent is:

1. A folding seat for looms comprising a bracket and means for adjustably attaching the same to the loom frame, a seat having 85 an integral arm mounted on said bracket and presenting flat under and end surfaces adjacent said pivot and a spring actuated plunger adapted alternatively to coöperate with either of said flat surfaces to lock the 90 same in horizontal operative position or in a substantially vertical inoperative position.

2. A folding seat for looms comprising a two-part bracket and means for attaching the same to the loom frame, the parts of 95 said bracket having upwardly extending ears to receive a pivotal shaft, one of said parts having an upwardly extending overhanging extension, a loom seat having an arm pivotally mounted upon said shaft and having an upwardly and rearwardly offset extension adapted to engage the extension on said bracket, flat surfaces upon the inner end of the arm of said loom seat and a plunger slidably mounted in said bracket 100 adapted alternatively to engage said flat surfaces to retain the loom seat in horizontal operative position, with said arm extension engaging the bracket extension or in substantially vertical inoperative position. 105

3. A folding seat for looms comprising a bracket having an L-shaped member presenting a wall adapted to engage the side of the loom frame and a coöperating member 115 abutting at one edge against said L-shaped member and formed to embrace the flanged edge of the loom frame and means for securing said bracket members together, a pivotal shaft mounted in said bearing 120 members, a loom seat having an arm pivotally supported by said shaft between said bracket members and presenting adjacent its pivotal end flat surfaces disposed in angular relation to each other, a plunger slidably mounted in one of said bracket members having a head adapted alternatively to engage said surfaces and resilient means for 125

- forcing the head of said plunger in contact with such surfaces.
4. A folding seat for looms comprising a bracket and means for attaching the same to the loom frame, a seat having an arm pivotally mounted on said bracket and presenting at its pivotal end flat surfaces disposed in angular relation to each other, and a plunger slidably mounted in said bracket having a flat face adapted alternatively to engage the flat surfaces on said arm to lock said seat in a horizontal operative position or in a substantially vertical inoperative position.
5. A folding seat for looms comprising a bracket and means for attaching the same to the loom frame, a seat having an arm pivotally mounted on said bracket and presenting at its pivotal end flat surfaces disposed in angular relation to each other, a plunger having a head provided with a flat face and a stem slidably mounted in a bore in said bracket, a helical spring surrounding said stem adapted to force the flat face of said plunger into engagement alternatively with the flat surfaces on said arm to lock said seat in a horizontal operative position

or in a substantially vertical inoperative position.

6. A folding seat for looms comprising a two-part bracket and means for attaching the same to the loom frame, the parts of said bracket having upwardly extending ears to receive a pivotal shaft, one of said parts having an upwardly extending overhanging extension, and a loom seat having an arm pivotally mounted upon said shaft and provided with an upwardly and rearwardly offset extension adapted to engage the extension on said bracket when the loom seat is in horizontal position.

7. A folding seat for looms comprising a bracket and means for attaching the same to the loom frame, a pivotal shaft mounted on said bracket, an overhanging extension, a loom seat having an arm pivotally mounted upon said shaft and provided with an extension adapted to engage the extension on said bracket and means for locking the loom seat in horizontal operative position or in substantially vertical inoperative position.

In testimony whereof I have signed my name to this specification.

ROBERT JAMIESON.
